UNITED STATES PATENT OFFICE

158,062

HANGER

Lucy F. Francis, Richmond, Va.

Application May 3, 1948, Serial No. 146,152

Term of patent 3½ years

(Cl. D33—8)

To all whom it may concern:

Be it known that I, Lucy F. Francis, a citizen of the United States, residing in the city of Richmond, State of Virginia, have invented a new, original, and ornamental Design for a Hanger, of which the following is a specification, reference being had to the accompanying drawing, forming part thereof.

I claim:

The ornamental design for a hanger, as shown.

LUCY F. FRANCIS.
